UNITED STATES PATENT OFFICE.

LOWELL C. WEINBERG AND HERBERT E. BRANNON, OF DAYTON, OHIO.

CARBURETOR AIR VALVE.

Application filed August 13, 1921. Serial No. 492,206.

This invention relates to carburetors in general and more particularly to a barometrically operated device for automatically regulating and controlling same.

Especially in aircraft internal combustion engines it has been found that the action of the carburetor varies in accordance with the change in barometric pressure. It is therefore proposed to provide automatic means for adapting the carburetor to function properly at all altitudes. This automatic means is to consist of a device actuated by the varying barometric pressure and to be connected to the intake manifold immediately above the carburetor so that the proportions of fuel vapor and air will be automatically regulated according to the prevailing barometric pressure. With the foregoing and other objects in view, which will appear as the description proceeds, the invention resides in the combination of parts and in the details of construction hereinafter described and claimed, it being understood that changes in the precise embodiment of the invention, herein disclosed may be made within the scope of what is claimed, without departing from the spirit of the invention, the specific embodiment of which is illustrated in the attached drawings, in which, Figure 1 is a vertical longitudinal section of the device on the line 1—1 of Figure 2.

Figure 2 is a bottom plan view of the air valve with parts of the carburetor shown in section.

Figure 3 is an enlarged detail section of the bellows construction.

As shown more clearly in Figure 2, 6 is the vertically extending pipe to the manifold and is provided with the usual butterfly valve 7, Venturi tube 4, and the carburetor jet 5 with the discharge opening 5'. Between the Venturi 4 and the butterfly valve 7, the pipe 6 is provided with a series of apertures 8 in the form of vertical slots, extending through and around the entire periphery of the pipe 6. A collar 3 is provided with a horizontally extending flange 11 and is securely fitted to pipe 6, by any suitable means which will enable said collar to be vertically adjusted with relation to the pipe 6.

Slidably mounted around the exterior of the pipe 6 is an inverted cup-shaped container comprising inner and outer side walls

2 and 2^b and a top plate 2^a provided with 55 apertures 9 in direct line with apertures 10 of the flange 11.

A flexible diaphragm of the bellows type 1 is arranged between the flange 11 and the top plate 2^a. In case a metallic bellows is 60 used the ends may be soldered or otherwise fastened to the plates 2^a and 11. However, if the bellows is made of fabric material such as rubberized silk it is found advisable to brace the walls thereof and add metallic 65 members for fastening the upper and lower extremities.

As shown more clearly in Figure 3, the upper and lower ends of the fabric bellows are connected to plates 2^a and 11 by means 70 of inner and outer retaining members 13 and 12, which are soldered to the plates 2^a and 11, there being a space provided between the members 13 and 12 for the reception of the ends of the bellows. 75

In order to restrict the expansion and contraction of the bellows so that the movement of the bellows will take place in a vertical plane, there are provided retaining rings 15 and 17 inside the rings 14 and 16 outside of 80 the bellows in order to prevent lateral expansion or contraction of said bellows.

Thus it will be seen that as the barometric pressure becomes less, due to changes in atmospheric conditions or an ascent to higher 85 altitudes, the bellows expands and consequently forces the container comprising walls 2, 2^a, and 2^b upwardly. The wall 2^b is adapted to slide on the exterior surface of the pipe 6; upon this upward movement the 90 slots 8 will be opened to allow the inrush of air from outside through the ports 9 and 10. The amount of inrushing air is thus regulated by the amount of expansion or contraction caused in the bellows by changes 95 in the prevailing barometric pressure.

It will be seen from the foregoing description that the flexible walls of the bellows will respond to the slightest variations in the barometric pressure, being compressed 100 when the barometric pressure increases and expanding when the pressure decreases, the movements of the flexible walls being transmitted by mechanism to the air regulating valve which will cause the minimum lost 105 motion and frictional interference. As the pressure decreases with increasing altitude, the sliding valve 2^b will gradually open the

intake slots thus gradually increasing the proportion of air admitted as compared to the combustible fuel.

We claim:

- 5 In combination, in a carburetor having an air inlet, a fuel inlet, and a mixture outlet, a throttle valve in said mixture outlet, a plurality of openings in the wall of said carburetor between the fuel nozzle thereof and
- 10 the throttle valve, a sleeve slidable on the exterior wall of said carburetor and having

openings adapted to be brought into registration with the openings in said carburetor wall, and means responsive to variations in atmospheric pressure to cause said openings to move into registration as the atmospheric pressure decreases.

In testimony whereof we have affixed our signatures.

LOWELL C. WEINBERG.
HERBERT E. BRANNON.
